J. H. BECKER

EXHAUST NOZZLE TIP FOR LOCOMOTIVES

Filed June 11, 1927

FIG. 1.

FIG. 3.

FIG. 2.

John H. Becker,

INVENTOR

BY *Victor J. Evans*

ATTORNEY

UNITED STATES PATENT OFFICE.

JOHN H. BECKER, OF PITTSBURGH, PENNSYLVANIA.

EXHAUST-NOZZLE TIP FOR LOCOMOTIVES.

Application filed June 11, 1927. Serial No. 198,139.

This invention relates to an exhaust nozzle for the exhaust steam pipe in the smoke box of a locomotive, the general object of the invention being to provide means for giving the steam escaping from the pipe a whirling motion so that a vacuum will be produced in the box which will improve the draft through the tubes, eliminate back pressure in the cylinders, which will result in a saving of fuel and water and prevent the flues from clogging up.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a sectional view through a portion of a locomotive, showing the invention in use.

Figure 2 is a section on line 2—2 of Figure 1.

Figure 3 is a plan view of the nozzle.

In these views, 1 indicates the steam exhaust pipe which is placed in the smoke box 3 of the locomotive and 4 indicates the improved nozzle which is fastened to the top of the pipe. This nozzle is formed with a cylindrical body having a flange 5 at its lower end which is bolted or otherwise secured to the flange at the top of the pipe 1. Blades or fins 6 are arranged within the upper part of the body, these blades being formed integral with the body. The blades are connected together

at their inner ends, as shown at 7, and each blade is slightly inclined to the vertical, as shown.

Thus it will be seen that the steam escaping from the pipe 1 will be given a whirling motion by the inclined blades which will produce a vacuum in the smoke box and in the flues so as to give a perfect draft through the flues, eliminating back pressure in the cylinders and thus increasing the efficiency of the locomotive. The invention will also produce a saving of fuel and water and will prevent the flues from clogging up with ashes. The improved nozzle can be fastened to the exhaust pipe as it is now constructed, and the whirling motion given the steam will be communicated to the products of combustion and this will prevent air being drawn into the smoke box through the stack.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

In combination with the steam exhaust pipe in the smoke box of a locomotive, a nozzle attached to the exhaust end of the pipe, diametrically arranged blades in the upper part of the nozzle and slightly inclined from the vertical to give the escaping steam a whirling motion, said blades being formed integral with the body of the nozzle and having their inner ends connected together.

In testimony whereof I affix my signature.

JOHN H. BECKER.
